DISPLAY RACK FOR BOTTLED GOODS

Lawrence W. Patterson, Santa Ana, Calif.

Application January 25, 1952, Serial No. 268,287

5 Claims. (Cl. 211—74)

1

This invention relates to merchandising racks and more particularly relates to a stand or rack for displaying and merchandising bottled goods, canned goods, and like articles having rigidity and uniformity of shape and height.

A disadvantage common to most display racks for bottled merchandise is that—if they are portable, which is highly desirable—they are excessively heavy and provided with all sorts of devices for preventing the merchandise from toppling and rolling while the racks are being wheeled or otherwise transported from one location to another. It is an object of this invention to provide a light, portable rack which so holds the merchandise and is so held by the merchandise that rack and merchandise together form a substantially rigid mass which may be wheeled about or jolted without breakage or dislocation of the displayed goods.

A particular advantage of my invention lies in connection with the display of bottled goods in small merchandising units. Many bottled goods are now packed in light un-covered cardboard containers, containing perhaps half a dozen bottles and spoken of as "Handypack Cartons." However, in self-service stores, a customer need not take a full carton but may remove one or two bottles as needed, and in time a large number of these cartons become partly emptied, so that the effect is lost of the merchandising suggestion that the customer take a full half-dozen bottles. Some stores attempt to sell Handypacks only as full units, but either as a result of pilferage or of less-than-unit sales, broken packs occur frequently and incite further pilferage or further small sales. This is particularly true when, in order to impress customers with large displays, goods are made available at a plurality of levels, as in pyramids or on a number of vertically arranged shelves. One of the objects of my invention is to make available to the customer only a limited number of these Handypack cartons at any one time, yet to permit a large volume of merchandise to be present and on display, and to have a fresh supply of full cartons or like containers automatically available when a previous limited supply has been exhausted.

Another object of my invention is to provide a light rack of skeleton structure which will afford visibility to a large amount of merchandise and yet hold the goods firmly in a mutually supporting mass so as to avoid breakage.

The invention possesses other useful features which will be pointed out as the following description of a presently preferred embodiment of the invention proceeds, or which will be apparent from said description considered together with the accompanying related drawing, in which,

Fig. 1 is a perspective view of a display rack 60

2

showing bottled goods in position on the base and on a lower separator of the rack; and

Fig. 2 is a side elevational view, showing additional upper separators in a raised position assumed by the separators when not occupied.

Having reference to the details of the drawing, my invention comprises a platform 3 preferably mounted on casters 4, for portability, and a back frame 5 secured rigidly to the platform and extending upwardly from one end thereof. At spaced intervals corresponding to the height of the bottles 6 to be displayed, or to the combined height of the bottles and the cartons 7 if such group containers are to be used, the back-frame 5 is provided with horizontal transverse bars 8. One or more vertical bars 9 are also provided, not only to brace the back frame but to provide anchorage for springs 10.

The horizontal bars 8 serve as hinge-pins upon which tray-frames 11 functioning as separators between tiers of goods disposed on the rack are hinged for vertical arcuate movement. The tray-frames 11 have an open grid-work form, each comprising a rim member 12 and a plurality of thin cross-members 13 extending transversely between opposite portions of the rim member 12. Preferably the cross-members 13 extend from the rear rims 14 of the tray frames 11, adjacent the back-frame 5, to the opposite or front rims of the tray-frames, so that the rearward ends of two or more of the cross-members 13 may be extended beyond the rear rims 14 and coiled to form hinge rings 15 pivoted on the horizontal bars 8. The cross-members 13 are secured to the lower sides of the rim members 12, so that the latter may act to retain merchandise disposed on the trays. The springs 10, anchored at their one ends to the vertical bars 9, are also pivoted upon the bars 8 and have their other ends anchored to the side portions of the rims 12, and urge the tray-frames 11 to swing upwardly to positions, shown in Fig. 2, in planes adjacent to the vertical plane of the back-frame 5.

It will be seen that while the back-frame 5 affords a mechanical stop to the upward swinging of the tray-frames 11, no in-built mechanical stop is provided to limit the downward swinging of the tray-frames to position below the horizontal. However, when the rack is loaded, downward movement of the tray-frames 11 is limited to the horizontal by the bottles of the lower tiers, such being made possible by spacing the cross-members 13 at intervals coinciding with the spacing of the bottles 6, which are arranged as illustrated in front-to-back rows. If the bottles are to be stacked individually, the cross-members 13 are spaced equally to the diameter of the bottles, and hence to the center lines of the rows of the bottles, and may be of sufficient

width to provide stability for a bottle centered thereon. If the bottles are stacked in cartons, the cross members 13 may be narrow rods, but again spaced and arranged to over-lie and under-lie the center lines of the rows of the bottles, allowing for the thickness of the cardboard walls of the cartons. The horizontal bars 8 and hinge rings 15 are arranged to permit the tray-frames 11 to attain the horizontal at vertical intervals corresponding to the height of the bottles 6 or the combined height of the bottles 6 and cartons 7, and the cross-members 13 will then rest upon the tops of the bottles beneath them. Thus a vertical series of compartments is formed, each compartment of the exact height required to contain the bottles. Moreover, since the tray frames function solely as load-transmitting separators between adjacent upper and under tiers of the bottles, all the bottles below the uppermost horizontal tray-frame 11 are firmly held in a substantially solid pack by the weight of the merchandise above them. With the bottles so held vertically, they will not shake or topple when the rack is moved about or is jolted. At the same time, the open grid or skeleton form of the tray-frames 11 permits good visibility of the merchandise supporting the uppermost horizontal tray-frame.

The springs 10 are tensioned to slightly overcome the weight of the tray-frame 11 to which they are attached, so that they are counterbalanced by the weight of a predetermined unit of merchandise resting upon the tray-frame. As the springs 10 and the tray-frames 11 are both pivoted on the horizontal bars 8, the relative mechanical advantage of the springs remains constant, and the force exerted may be calculated as a function of the spring tension. Spiral springs of the type shown may be made to have substantially constant tension over considerably more than the ninety degree angle of movement shown to be required, and with constant mechanical advantage the spring action may be made gentle from the start of the upward movement, the tray-frame rising gently to its vertical limit, and uncovering the merchandise in the compartment next below.

I wish it understood that modifications may be made in the form of my rack without departure from the spirit of my invention, and that I desire to be protected in my invention to the full scope of the novelty set forth in the appended claims.

Claim:

1. A rack for displaying and merchandising bottled and like goods having rigidity and uniform height comprising, in combination, a base, a back frame extending upwardly from an edge of said base and a separator member hinged to the back frame for vertical arcuate movement above and below the horizontal and serving, when supported in the horizontal plane by goods disposed below same, to transmit the load of goods disposed thereon to the goods disposed below and thence to the base, and spring means interconnecting the back frame and separator member for urging the latter upwardly to a position adjacent the back frame upon removal of the last unit of goods disposed on said separator member.

2. A rack as set forth in claim 1, wherein the tension of the spring means is not substantially greater than that required to support the weight of the separator member in the horizontal plane, whereby said member moves upwardly at a slow

rate upon removal of the last unit of goods as aforesaid.

3. A rack for displaying and merchandising bottled and like goods having rigidity and uniform height comprising, in combination, a base for supporting a lowermost tier of the goods, a back frame extending upwardly from an end of the base, and a plurality of separator members hinged to the back member for vertical arcuate movement above and below the horizontal and along horizontal hinge lines which are spaced from the supporting surface of the base and from one another a distance corresponding to the vertical height of the goods, said separator members serving to retain goods disposed thereon in tiers and to transmit the load of the upper tiers to the under tiers and thence to the base, and spring means interconnecting each of the separator members with the back frame and being operative to urge said separator members individually to a position adjacent the back frame upon removal of the last unit of goods therefrom.

4. A rack for displaying and merchandising bottled and like goods having rigidity and uniform height comprising, in combination, a base for supporting a plurality of the goods arranged thereon in front-to-back rows, a back frame extending upwardly from the back edge of the base and including a plurality of transverse bars spaced from the supporting surface of the base and from one another a distance corresponding to the vertical height of the goods, a plurality of separator members hinged to said bars for vertical arcuate movement above and below the horizontal, said separator members each comprising a frame and a plurality of cross members extending between the front and back sides of the frame and being spaced from one another a distance corresponding to the distance between the center lines of said rows, and spring means interconnecting each of the separator members and the transverse bar to which it is hinged for urging said separator members individually to a position adjacent the back frame upon removal of the last unit of goods therefrom, the construction and arrangement being such that said cross members center on the goods disposed immediately beneath same and thereby the separator members serve to transmit the load of the goods disposed thereon in the aforesaid front-to-back row arrangement to the goods below the same and thence to the base.

5. A rack as set forth in claim 4, wherein the cross members of each separator member are secured to the under side of the frame thereof, whereby the latter serves as a retaining rim, and are extended rearwardly beyond the back side of the frame and terminate in hinge rings which are connected to one of said transverse bars so as to provide for the vertical arcuate movement of said separator member as aforesaid.
